UNITED STATES PATENT OFFICE.

MARIE OCTAVIE HAWORTH-BOOTH, OF LONDON, ENGLAND.

DESIGN FOR A BOTTLE OR CONTAINER.

58,090.

Specification for Design.

Patented June 7, 1921.

Application filed October 13, 1920. Serial No. 416,772. Term of patent 7 years.

To all whom it may concern:

Be it known that I, MARIE OCTAVIE HAWORTH-BOOTH, a subject of the King of Great Britain, residing at 17 Grove End road, London, England, have invented a new, original, and ornamental Design for a Bottle or Container Particularly for Scents or Perfumes, of which the following is a specification, reference being had to the accompanying drawing, forming a part thereof.

Fig. 2 is a front view showing the stopper removed.

Fig. 3 shows the stopper which when fitted in the bottle constitutes one corner thereof.

Fig. 4 is a side showing the inclined face and the hole into which the stopper is fitted.

Fig. 5 is a perspective view of the complete bottle shown in Fig. 1.

I claim:

The ornamental design for a bottle or container, as shown.

MARIE OCTAVIE HAWORTH-BOOTH.
